Primary Examiner—Susan Bennett Hattan(74) *Attorney, Agent, or Firm*—PatentBest; Andrew McAleavey(57) **CLAIM**

The ornamental design for a bottle cap, as shown and described.

DESCRIPTION

FIG. 1 is a perspective view of the bottle cap, taken from the underside, illustrating our new design;

FIG. 2 is a front elevational view of the bottle cap;

FIG. 3 is a rear elevational view of the bottle cap;

FIG. 4 is an elevational view of one side of the bottle cap;

FIG. 5 is an elevational view of the other side of the bottle cap;

FIG. 6 is a top plan view of the bottle cap; and,

FIG. 7 is a bottom plan view of the bottle cap.
